UNITED STATES PATENT OFFICE.

PETER B. VREDENBURG, OF MECHANICSVILLE, NEW YORK.

HAMMER.

1,042,177.

Specification of Letters Patent.

Patented Oct. 22, 1912.

Application filed February 15, 1911. Serial No. 608,730.

To all whom it may concern:

Be it known that I, PETER B. VREDENBURG, a citizen of the United States, residing at Mechanicville, in the county of Saratoga and State of New York, have invented new and useful Improvements in Hammers, of which the following is a specification.

This invention relates to improvements in hammers, and the object of the invention is to provide a hammer so constructed and provided with means whereby the implement may be used for the ordinary purposes of a hammer and whereby long nails may be readily pulled without bending and with only a comparatively small exertion upon the part of the operator.

With the above objects in view and others which will appear as the nature of the invention progresses, the invention resides in the novel construction of hammer heads hereinafter fully described and claimed.

In the accompanying drawings, Figure 1 is a side elevation of a hammer constructed in accordance with the present invention. Fig. 2 is a longitudinal sectional view of the same.

In the drawings the numeral 1 designates the hammer head. This head is provided with the usual socket 2 which is adapted for the reception of the handle 3. The heel 4 of the hammer is projected a suitable distance beyond the socket and integrally formed with the front portion of the hammer between the socket 2 and the heel 4 is the arched claw member 5. This member 5 is constructed at a desired arc from the socket 2 and projects a suitable distance above and beyond the said socket. The terminal of the arched claw is bifurcated and has the inner walls provided thereby beveled so that the same can readily engage with the heads of the nails to be extracted.

The numeral 6 designates a web projecting from the socket 2 and connecting the under face of the claw 5. The arched claw

5 adjacent its juncture with the hammer proper is formed with an inclined opening 7, the latter being adapted for the reception of a suitable screw 8 which enters the forward portion of the handle 3 and securely retains the handle upon the hammer.

From the above description taken in connection with the accompanying drawings, the simplicity of the device as well as the advantages thereof will, it is thought be apparent to those skilled in the art to which such inventions appertain, it being noted that the arched claw provides a fulcrum whereby nails of great length may be extracted. It will be further noted that the member 6 reinforces both the claw and head of the hammer and it will be still further noted that by providing the arched claw with the countersunk opening, the handle of the hammer may be sustained within the socket thereof without the use of wedges or analogous devices.

Having thus fully described the invention, what I claim as new, is:—

A hammer head comprising a socket member provided with a heel, the said socket being integrally formed with a web which is arranged diametrically opposite the heel, an arched claw connected with the web and extending rearwardly beyond the socket, a curved member integrally formed with the arched claw, and extending beyond the outer face of the socket and connected thereto at the juncture of the heel with the socket, and said arched claw having an inclined opening directed toward the bore of the socket and adapted for the reception of a handle securing element, substantially as and for the purpose set forth.

In testimony whereof I affix my signature in presence of two witnesses.

PETER B. VREDENBURG.
